P. S. Vedder, of Troy, New York.
Assigned to John S. Merritt Peckham, of Utica, N.Y.
Letters Patent No. 1336, dated Oct. 2, 1860.

The schedule referred to in these Letters Patent and making part of the same.

To all whom it may concern:

Be it known that P. S. Vedder, of the City of Troy, in the County of Rensselaer, and State of New York, have invented or produced a new and original design for Stove registers, and I do hereby declare that the following is a full, and exact description of the same, reference being had to the accompanying drawing and to the letters of reference marked thereon.

Figure 1. represents a front view of the said Stove register.

A. is the register plate.

B. is the damper.

C. the nut to regulate the draught.

What I claim as my invention and desire to secure by Letters Patent, is the general design and configuration of said Stove register.
